UNITED STATES PATENT OFFICE

118,745

DESIGN FOR AN AUTOMOBILE DIRECTION INDICATOR

Jose P. Sandejas, Manila, P. I., assignor of one-tenth to Manuel Lim, Manila, P. I.

Application September 19, 1939, Serial No. 87,289

Term of patent 14 years

To all whom it may concern:

Be it known that I, Jose P. Sandejas, a citizen of the Philippine Islands, residing at Manila, Philippine Islands, have invented a new, original, and ornamental Design for an Automobile Direction Indicator, of which the following is a specification, reference being had to the accompanying drawing forming part thereof.

In the drawing:

Fig. 1 is a front elevation of an automobile direction indicator showing my new design; and Fig. 2 is an end view thereof.

I claim:

The ornamental design for an automobile direction indicator, as shown.

JOSE P. SANDEJAS.
